UNITED STATES PATENT OFFICE.

FRANK TALARICO, OF PHILADELPHIA, PENNSYLVANIA.

TALKING-MACHINE.

1,388,980.

Specification of Letters Patent. Patented Aug. 30, 1921.

Application filed April 10, 1920. Serial No. 372,955.

To all whom it may concern:

Be it known that I, FRANK TALARICO, a citizen of the United States, residing at Philadelphia, in the county of Philadelphia and State of Pennsylvania, have invented certain new and useful Improvements in Talking-Machines, of which the following is a specification.

One object of my invention is to provide an improved sound conducting and amplifying means which can be easily and quickly placed in operative position on any supporting structure adjacent a record; thereby doing away with the necessity of employing complicated and expensive cabinets and amplifying means such as now commonly employed in connection with talking machines.

Another object is to so construct the device of my invention that it can be easily manipulated so as to transmit sounds and when not desired for use the same can be moved into a position out of the way so as to permit a record to be removed from the turntable and another record placed thereon.

A further object is to provide a device having the above advantages and which will accurately produce a large volume of tone.

These objects, and other advantageous ends which will be described hereinafter, I attain in the following manner, reference being had to the accompanying drawings in which—

Figure 1 is a side elevation of my invention showing the same in the position which it occupies when playing a record.

Fig. 2 is a top plan view of Fig. 1.

Fig. 3 is a view of similar character to Fig. 2 showing the device in a position when not in use,

Fig. 4 is a sectional elevation taken on the line 4—4 of Fig. 1.

Fig. 5 is a fragmentary perspective view showing a certain feature of construction of a part of my invention, and

Fig. 6 is a fragmentary view showing a modification of adjustable means which forms a part of my invention.

Referring to the drawings, 7 represents a supporting structure which may be of any character such as the top of a cabinet or box upon which is mounted the usual turntable 8 for supporting a record 9.

The device of my invention consists of two hollow pedestals 10 and 11. Each of the pedestals includes a hollow base 12 which is

open at its top and flares downwardly to a closed bottom 13. The sides of the bases 12 have apertures 14. The bases 12 are joined together by a bar 15 preferably made of resilient metal which includes a central hole 16 through which a screw 17 can be inserted to secure the device to the supporting structure 7. Screws 18 extend downwardly through screw threaded holes in the bases 12 and engage within screw threaded cavities 19 in legs 20. The bottoms of the legs are adapted to engage the supporting structure 7 at positions remote from the central screw 17 and the purposes of these legs 20 will be described hereinafter. The pedestal 10 includes a nipple 21 which depends into the top of its base 12 and is provided with a flange 22 for engagement with the top of the base, as clearly shown in Fig. 4. The nipple 21 may be secured to the base by screws 23. The upper end of the nipple 21 is turned toward the pedestal 11 and is provided with a lip 24 which abuts a similar lip 24 on the curved upper end of a nipple 25 which forms a part of the pedestal 11; said nipple 25 being of similar construction to the nipple 21 and depending into the base 12 of the pedestal 11. The upper ends of the nipples 21 and 25 are preferably secured together by a bar 26; said bar in the present instance being illustrated as secured by screws 27.

A tone arm 28 has a front section 29 and a rear section 30. The front section supports a sound box 31 which may be of any desired construction and this front section has an upwardly extending part 32 pivotally connected to the lower forward part 33 of the rear section 30. The rear section 30 has a T-shape tail 34 which provides hollow open end extensions 35 and 36. These extensions are respectively pivoted within the upper open ends of the nipples 21 and 25; said lips 24 of the nipples serving as a supporting ledge so as to provide an extended bearing for the tail 34 between the ends of the nipples 21 and 25.

The pivotal connection between the front and rear sections of the tone arms permits the front section to swing in a horizontal plane and the pivotal connection between the tail 34 of the rear section and the nipples 21 and 25 permits the tone arm, as a whole, to swing in a vertical plane so that a universal movement is possible. A support 37 is secured to the pedestal 10 and

serves, when the device is not desired for use, to support the sound box 31 in the position shown in Fig. 3; the arrangement being such that the front section can be swung 5 on its pivot and the rear section raised so as to lift the sound box over the hooked front extension 38, after which the sound box can be lowered into said hooked extension and will be securely held therein so 10 as not to be accidentally jarred or moved therefrom.

By providing the legs 20 as above described they can be turned on the screws 18 into abutment with the supporting structure 15 7 so as to keep the bar 15 in its raised position; sufficient tension being imposed upon said bar 15 to cause the latter to re-act, due to its resilient characteristic, and thereby keep the legs in firm contact 20 with the supporting structure; preventing any chance of noise by vibration and also for keeping the entire device from accidental swinging on the screw 17 as a pivot. In this manner the device can be secured 25 by a single screw, such as 17, to a supporting structure and at the same time accidental movement and noise will be prevented.

In Fig. 6 I have illustrated one of the 30 legs 20 provided with rubber 39 for engagement with the supporting structure and if desired each of the legs 20 can be provided with rubber or other soft material so as not to injure the supporting structure. Furthermore when rubber or other resilient 35 material is provided on the legs 20 a resilient cushioning action is provided to take up any jar of the parts caused by vibration.

In the use of the device the vibrations 40 set up by the sound box cause sound waves to travel through the front and rear sections of the tone arm to the T-shape tail 34; a part of the sound passing through the 45 extension 35 and 36 into said nipples 21 and 25. The sound then passes into the flared bases 12 of the pedestals and the latter provide amplifiers therefor and permit the amplified sound to pass outwardly 50 through the lateral apertures 14 in a distinctly audible character.

While I have described my invention as taking a particular form, it will be understood that the various parts of my inven-

tion may be changed without departing from 55 the spirit thereof, and hence I do not limit myself to the precise construction set forth, but consider that I am at liberty to make such changes and alterations as fairly come 60 within the scope of the appended claims.

Having thus described my invention, what I claim as new and desire to secure by Letters Patent is:—

1. The combination in a talking machine 65 of a plurality of hollow pedestals having apertures therein; a tone arm communicating with said pedestals; sound reproducing means on said tone arm; means connected to said pedestals and to a supporting structure; and legs positioned at points remote from 70 said latter means for engagement with said supporting structure whereby tension can be placed upon said latter means for the purpose of holding said legs in contact with 75 said supporting structure; substantially as described.

2. The combination in a talking machine 80 of a plurality of hollow pedestals having apertures therein; a tone arm communicating with said pedestals; sound reproducing means on said tone arm; common means for connecting said pedestals to a supporting structure; and adjustable legs connected to 85 said pedestals at positions remote from said common means for engagement with said supporting structure; substantially as described.

3. The combination in a talking machine 90 of a supporting structure; a sound outlet pedestal; means secured to said supporting structure and serving to limit the upward movement of the pedestal from the supporting structure; and legs in screw threaded connection with said pedestal and adapted 95 to engage said supporting structure, said legs when turned in one direction being operative to exert pressure upon said supporting structure and thereby hold said pedestal under tension against said first means; substantially as described.

In testimony whereof I have signed my name to this specification in the presence of two subscribing witnesses.

FRANK TALARICO.
